MERIAN H. DICKINSON, OF SEATTLE, WASHINGTON, AND JOSEPH H. DICKINSON, OF WINTER PARK, FLORIDA, ASSIGNEES TO LIDGERWOOD MANUFACTURING COMPANY, OF NEW YORK, N. Y., A CORPORATION OF NEW YORK.

OVERHEAD CABLEWAY SKIDDING AND LOADING EQUIPMENT.

Application filed January 14, 1925. Serial No. 2,268.

Our invention more particularly relates to a novel mounting for overhead skidding and loading equipment whereby the same may conveniently and effectively be transported.

5 Our invention will best be understood by reference to the accompanying drawing in which we have illustrated one embodiment thereof, and in which the single view is a side elevation.

10 Referring to the drawing, 10 is a movable support, here illustrated as comprising two platforms 12 and 12' flexibly connected together, and which are preferably alike, each of which is mounted on logging or special

15 trucks 13, engaging track rails 14. It will of course be understood that the platforms may be flexibly connected together merely by lowering the spar or boom, or both, onto the other platform, and without the provision

20 of special connecting means between the platforms, such as illustrated. An additional base or platform 11 for the machine is mounted upon the platform 12' and is provided with suitable supports 15, adapted,

25 when the machine is in its stationary position, to straddle the track rails 14. It is to be understood that, in the embodiment illustrated, the base 11 is a part of the log skidding machine and for moving purposes may

30 be lowered on to the platform 12', or it may be supported on stationary blocks and jacks in the same way as shown in patent of Joseph H. Dickinson, No. 936,425, Oct. 12, 1909. In case of a very long spar, the latter will reach

35 beyond the loading boom and rest at another point on the same member on which the end of the loading boom is resting.

Mounted on the platform 12' is a supporting vertical framework 16 of any suitable

40 type and carrying the swinging or pivoted spar 17, the latter being fulcrumed, as at 18, suitable universal trunnions preferably being provided on the spar for this purpose, which trunnions are preferably the same as or similar to those shown in patent of J. H. Dickinson, 936,425, October 12, 1919, whereby the

45 spar has movement in any direction. We have illustrated the spar 17 in a diagrammatic manner. It will be understood that it may

50 be formed of structural steel or otherwise, as desired. The spar 17 and other movable parts of the machine are illustrated in their operating positions in full lines, and in the positions which they occupy when being

transported in dotted lines. The spar 17 is 55 illustrated as provided with a tail portion 171, to the end of which is attached one of the blocks 19 of a block and tackle 20, the other block 21 being attached to the platform 11. The free end 22 of the rope for the block 60 and tackle 20 is wound upon a drum 23, which may be operated by an auxiliary or utility engine, indicated generally at 231. We have not illustrated the other cables which are 65 wound on the drums of the utility engine, nor have we, in general, illustrated the cables wound upon the drums of the hoisting engine, illustrated generally at 24, or those wound upon the drums of the skidding engine, illustrated generally at 25, as these connections 70 constitute no part of our present invention, and the same are omitted for clarity of both illustration and description. It will, of course, be understood that when the spar 17 is in its elevated operating position, as illustrated in full lines, the same will be suitably guyed, and a suspended overhead cable is 75 suitably supported at one end on the upper end of the spar. The usual cables used in skidding operations will be employed and are 80 wound upon the drums of the skidding engine 25 and pass over sheaves near the top end 172 of the spar.

The loading equipment comprises a loading boom 26, which, in the form illustrated, 85 is mounted on a turntable 27 on the platform 11, so that the loading boom may be swung horizontally, as well as vertically. The loading boom is pivoted at 28 so that the same 90 may be raised and lowered in a vertical plane by a suitable block and tackle 29, through a swinging arm 30, pivoted at 31 on the frame 16. The blocks and tackle 29 comprise a block 311 on the free end of the arm 30 and a block 32 mounted on the frame, the free 95 end 33 of the cable for this block and tackle passing over a sheave 34 on the frame and wound upon a drum 35 which, in this case, is operated by the skidding engine, since the skidding operations are discontinued when the equipment is being prepared for transportation and is actually being transported. The free end of the arm 30 is connected to 100 the end of the loading boom 26 by a suitable supporting cable 36, so that as the free end of the cable 33 is wound upon the drum 35, the arm 30 is raised, thereby raising the boom 26, and when the cable 33 is paid out from 105

the drum 35; the arm 30 and the boom 26 are lowered.

When it is required to move platform 11, car 12 is moved into place and boom 26 and spar 17 are lowered and rest upon car or platform 12. Heretofore the spar 17 has been lowered as far as it may be, leaving its free end practically unsupported, and under such circumstances, the free end of the skidding 10 spar and the free end of the loading boom being unsupported, the center of gravity of the equipment is necessarily high, and this high center of gravity combined with the swinging action of the spar and boom in the process of 15 moving, has resulted in the overturn of the entire machine, thereby causing serious accidents. This swinging action is traceable to curvature and irregularities of the track. Our invention provides means for supporting 20 the pivoted member or members, which, in this case, comprises the loading boom and the skidding spar, at points remote from their pivotal points and preferably on an auxiliary movable platform, usually adjacent to the 25 platform on which the machine is mounted. In the form shown, the auxiliary car 12, which is in the form of a flat car, is provided with a special supporting block 37, on which the loading boom 26 is supported at a point remote 30 from its pivotal point, and preferably near or at the end thereof, as illustrated in the drawing. In the form shown, the end of the loading boom 23 may be lowered directly into supporting engagement with the block 35, 35 the same slidably engaging the same so that the supporting portion of the boom 26 may move relatively to the block 35 under changes in grade curvature and under irregularities in the track. Preferably the end of the boom 40 26 is equipped with a plate or plates 38, provided with a roller 39, engaging the block 37, so as to provide easy relative movement between the two.

In the form shown, the end 172 of the spar 45 17 may be lowered into supporting engagement with the boom 26, so that the loading boom and skidding spar are both supported from below at points remote from their pivotal points, and preferably on a second or auxiliary movable platform. In the form shown, the end of the spar engages a specially provided roller 40, with which the plate or plates 38 are provided. It will, of course, 50 be understood that members, such as timbers, may be interposed between the supporting portion of the spar and the supporting portion of the boom.

When the machine is in operation, the parts 55 occupy the positions illustrated in full lines, the spar occupying an upright position and the loading boom being moved in accordance with the operations. When the device is to be transported, the end of the loading boom 26 is lowered by the blocks and tackle 29 into engagement with the block 37 on the auxiliary

car 12, and the end of the spar 17 is then lowered into supporting engagement with the boom by means of the blocks and tackle 20. By lowering either or both the boom and spar into supporting engagement with the part of the base remote from the pivotal points, the boom or spar or both are prevented from swinging and, at the same time, the center of gravity of the equipment is lowered, thereby not only relieving the equipment from the strains that would result from the swinging of the boom and spar, but minimizing the tendency of the equipment to overturn.

By mounting the boom for universal movement on the first platform, the end of the boom when lowered into position on the second platform and in the position indicated in dotted lines in the figure, the end of the boom easily follows the second platform when going around curves. In the absence of such universal movement, that is to say, if the boom were merely pivoted for vertical movement, then one of the two cars supporting the boom when going around a curve would be overturned because of the failure of the boom to move laterally. Similarly, by mounting the spar on universal trunnions in the manner illustrated in the Dickinson patent above referred to, the end of the spar follows the second platform without overturning the car or cars.

We claim:—

1. In combination, two movable platforms spaced from each other, each being mounted on trucks adapted to engage track rails, a hoisting boom mounted for horizontal movement on one of said platforms and pivotally mounted for movement in a vertical plane, and means for lowering said boom into supporting engagement with the other platform, a roller bearing being provided between said boom and said other platform.

2. In combination, two spaced movable platforms, each being mounted on trucks adapted to engage track rails, a hoisting boom mounted for universal movement on the first of said platforms, a supporting spar mounted on trunnions on said first platform, and means for lowering the ends of the boom and of the spar into position to be supported by the second platform, a roller bearing being provided between said boom and said second platform and between said spar and said boom when in lowered positions.

3. In combination, a first and a second movable device spaced from each other, a boom mounted for universal movement on the first of said devices, a spar mounted for movement in a vertical plane on the first of said devices, the supports for said boom and spar being spaced from each other, and means for lowering said boom and said spar into supporting engagement with said second device.

4. In combination, a first and a second movable device spaced from each other, a

boom mounted for universal movement on the first of said devices, a spar mounted for movement in a vertical plane on the first of said devices, the supports for said boom and spar 5 being spaced from each other, and separate means for lowering said boom and said spar into supporting engagement with said second device.

5. In combination, a first and a second 10 movable device spaced from each other, each being mounted on trucks adapted to engage track rails, a hoisting boom mounted for universal movement on the first of said devices, a supporting spar mounted on said first device for movement in a vertical plane, means 15 for lowering the end of the boom into supporting engagement with the second device, and means for lowering the end of the spar into position to be supported by the end of the 20 boom, a member being provided between the boom and the spar when in lowered position for permitting relative movement between the same.

6. In combination, a first and a second 25 movable device spaced from each other, each being mounted on trucks adapted to engage

track rails, a hoisting boom mounted for universal movement on the first of said devices, a supporting spar mounted on said first device and having movement in a vertical plane, and 30 means for lowering the ends of the boom and of the spar into position to be supported by the second device, members being provided between said boom and said second device and between said spar and said boom for permitting relative movement between the boom and the second device, and between the spar and the boom when they are in lowered position.

7. In combination, two spaced movable 40 platforms, each being mounted on trucks adapted to engage track rails, a hoisting boom mounted for universal movement on the first of said platforms, a supporting spar mounted on trunnions on said first platform, 45 means for lowering the ends of the boom and of the spar into position to be supported by the second platform, and means for supporting the ends of said boom and said spar on said second platform.
